UNITED STATES PATENT OFFICE.

LEWIS A. CHAMBERLIN AND CHARLES H. WILLIAMS, OF DE SOTO, MISSOURI.

DENTAL INSTRUMENT.

1,105,755.

Specification of Letters Patent. Patented Aug. 4, 1914.

Application filed May 14, 1914. Serial No. 838,571.

To all whom it may concern:

Be it known that we, LEWIS A. CHAMBERLIN and CHARLES H. WILLIAMS, citizens of the United States, residing at De Soto, in the county of Jefferson and State of Missouri, have invented certain new and useful Improvements in Dental Instruments; and we do declare the following to be a full, clear, and exact description of the invention, such as will enable others skilled in the art to which it appertains to make and use the same.

Our invention relates broadly to improvements in dental instruments and more particularly to pin extractors.

The primary object of the invention is to provide a device of this character which may be simply and inexpensively constructed and which will be well adapted to the purpose for which it is designed.

A secondary object of the invention is to construct the entire device in such a manner as to allow the same to be readily disassembled for the purpose of cleaning and sterilizing.

A still further object is to so position a clamp, to be described, as to prevent undue springing of the jaw members.

With these objects in view, the invention resides in certain novel features of construction and combination herein described and claimed and shown in the drawings wherein:

Figure 1 is a side elevation of a pin extractor constructed in accordance with our invention. Fig. 2 is an edge view thereof. Fig. 3 is a central vertical section. Fig. 4 is a section taken at right angles to Fig. 3 and substantially upon the line 4—4 of Fig. 1, and Figs. 5, 6 and 7 are horizontal sections taken respectively upon the lines 5—5, 6—6, and 7—7 of Fig. 1.

In the accompanying drawings, we have shown our invention as comprising a fixed jaw member 1, a movable jaw member 2, a stop member 3, an operating screw 4, and a clamp 5 whereby said jaw members may be moved toward each other.

The fixed jaw member 1 comprises an upright rectilinear bar 6 which is preferably rectangular in cross section, said bar being provided with, at one end, a transversely projecting ear 7 through which the shank of the operating screw 4 is swiveled and at its opposite end, with an inwardly curved jaw 8 which is preferably reduced in thick-

ness as indicated at 9 and roughened or serrated on its active face. The bar 6 is further provided with a transverse slot 10 which is disposed at a suitable point, said slot 10, the ear 7 and jaw 8 lying in the 60 same upright plane.

The movable jaw member 2 comprises an upright rectilinear bar 11 which, like the bar 6, is preferably rectangular in cross section and is provided, on one end, with a transversely extending arm 12 having its 65 terminal reduced in width as indicated at 13 and loosely mounted within the slot 10, the opposite end of said bar 11 being provided with an inwardly curved jaw 14, which, like the jaw 8, is reduced in width and serrated upon its active surface.

By reference to the drawings, it will be clearly seen that the jaws 8 and 14 coact when the parts are assembled, said jaws being forced toward each other by means of the clamp 5, the latter being here shown in the form of a rectangular yoke 15 which is provided, at one end, with a stud receiving opening 16 in which a stop stud 17, carried 75 by the jaw member 1, is seated, the opposite end of said yoke being preferably enlarged at its central portion and provided with a threaded bore in which a clamping screw 18 is mounted, the inner end of said 80 screw bearing against the outer surface of the member 2 and thereby moving said member toward the member 1 when tightened.

Interposed between the members 1 and 2 90 is the stop member 3, the latter comprising a rectilinear bar 19 having one of its ends bifurcated as indicated at 20 to straddle the reduced terminals of the jaws 8 and 14, the opposite end portion of said stop member 95 being preferably thickened and provided with a transverse slot 21 which receives the arm 12, the extreme end of said slotted portion being provided with a threaded bore with which the threads of the operating 100 screw 4 are engaged.

With the parts as above described, the operation of the device is as follows: The jaws 8 and 14 are positioned upon the pin P to be extracted and the bifurcated end of the stop member 3 is positioned in contact with the outer surface of the root R. The clamping screw 18 is now operated to cause said jaws to rigidly clamp the pin P after which the operating screw 4 is turned 110.

in a proper direction to cause the jaw members to move upwardly, thus effectually extracting the pin.

From the foregoing description, taken in connection with the accompanying drawings, it will be seen that we have produced an extremely simple pin extracting device, yet one which will effectually perform the functions for which it is desired and which 10 may be readily disassembled for the purpose of cleaning and sterilizing.

Particular emphasis is laid upon the location of the clamp 5 and its mounting since, by its location, the jaws 8 and 14 may be 15 moved into forcible contact with the pin, little yielding, on the part of the members 1 and 2, being allowed. By the herein described mounting of the clamp 5, it will be seen that in order to remove the same, it is 20 simply necessary to retract the screw 18 to an extent sufficient to allow the stud 17 to be disengaged from the opening 16, whereupon said clamp may be readily removed thus allowing the movable member 2 to be 25 disengaged from the members 1 and 3, which latter may be entirely removed by the proper actuation of the operating screw 4.

We have described our invention with 30 considerable minuteness but we do not wish to be limited to details of construction other than those amplified in the appended claims.

Having thus described our invention, what we claim as new and desire to secure 35 by Letters Patent is:

1. A device of the character described comprising a fixed rectilinear jaw member having a transverse ear at one end, a transverse jaw at its opposite end, and a transverse slot intermediate its ends, the ear, the 40 jaw, and the slot lying in the same longitudinal plane, a rectilinear movable jaw member lying substantially parallel to said fixed member and spaced therefrom, said movable member having a transverse extension on one end and a transverse jaw on its opposite end, said extension having a reduced terminal 45 slideable in said slot, a rectilinear stop member interposed between said fixed and movable jaw members and having a bifurcated portion straddling said jaws and a transversely and longitudinally slotted portion receiving said transverse extension, a clamp for moving said movable jaw toward 50 the fixed jaw and a set screw swiveled in said ear and having a threaded engagement with the adjacent end of said stop member.

2. A device of the character described comprising a fixed rectilinear jaw member 60 having a transverse ear at one end, a transverse jaw at its opposite end, and a trans-

verse slot intermediate its ends, the ear, the jaw, and the slot lying in the same longitudinal plane, a rectilinear movable jaw member lying substantially parallel to said fixed member and spaced therefrom, said movable member having a transverse extension on one end and a transverse jaw on its opposite end, said extension having a reduced terminal slideable in said slot, a rectilinear stop member interposed between said fixed and movable jaw members and having a bifurcated portion straddling said jaws and a transversely and longitudinally slotted portion receiving said transverse extension, a transverse clamping yoke embracing the two jaw members and the stop member, coacting stops carried by one jaw member and by one end of the yoke, a clamping screw having a threaded engagement with the opposite end of the yoke and bearing against the other jaw member and a set screw swiveled through said ear and having a threaded engagement with the adjacent end of the stop member. 85

3. A device of the character described, comprising a fixed rectilinear jaw member having a transverse ear at one end, a transverse jaw at its opposite end, and a transverse slot intermediate its ends, the ear, the 90 jaw, and the slot lying in the same longitudinal plane, a rectilinear movable jaw member lying substantially parallel to said fixed member and spaced therefrom, said movable member having a transverse extension on one end and a transverse jaw on its opposite end, said extension having a reduced terminal slideable in said slot, a rectilinear stop member interposed between said fixed and movable jaw members and having a bifurcated portion straddling said jaws and a transversely and longitudinally slotted portion receiving said transverse extension, a transverse clamping yoke embracing the two 95 jaw members and the stop member and having in its opposite ends a stud receiving opening and a threaded opening, a stop stud carried by one jaw member and disposed in said stud receiving opening, a clamping screw in the threaded opening and bearing 100 against the other jaw member and a set screw swiveled in said ear and having a threaded engagement with the adjacent end of the stop member. 105

In testimony whereof we have hereunto 110 set our hands in presence of two subscribing witnesses.

LEWIS A. CHAMBERLIN.
CHARLES H. WILLIAMS.
